UNITED STATES PATENT OFFICE

EDWIN M. BASSLER, OF CHICAGO, ILLINOIS, ASSIGNOR TO D. J. MURRAY MANUFACTURING COMPANY, OF WAUSAU, WISCONSIN, A CORPORATION OF WISCONSIN

HEAT TRANSFER APPARATUS

Application filed August 2, 1930. Serial No. 472,533.

This invention relates to heat transfer apparatus, and relates particularly to such apparatus comprising a hollow header, supply and return manifolds connected to opposite ends thereof, adapted for supplying a thermal agent to said header, and a fan mounted in association with said apparatus for directing a current of air over or through said header.

10 A particular object of the invention is to provide improved and simplified means for mounting and supporting the apparatus, whereby the bottom manifold will sustain the entire weight thereof, thus relieving its parts, other than the bottom manifold, and particularly the joints connecting the manifolds with the header from all stresses due to the weight of the apparatus—rendering it possible to use relatively light and inexpensive fittings.

20 Further objects of the invention are to provide a fitting of new and novel construction for connecting the manifolds with the header or headers of the apparatus, which will be simple in construction, strong and durable; which will be relatively inexpensive to manufacture and install; which can be effectively sealed to provide fluid-tight joints between the manifolds and header or headers; which will reduce the number of screw joints

25 necessary for connecting the manifolds with the header or headers; and which will reduce the over-all dimensions of the apparatus between the remote sides of the manifolds to a minimum.

30 To effect the various objects of the invention, my improved heat transfer apparatus comprises the various features, combinations of features and details of construction hereinafter described and claimed.

35 In the accompanying drawings in which the invention is fully illustrated,

Fig. 1 is a side view of heat transfer apparatus embodying my invention and improvements.

40 Fig. 2 is an enlarged sectional view of heat transfer apparatus embodying my invention and improvements, the headers and a portion of the lower manifold being shown in elevation.

45 Fig. 3 is a detached top plan view, partly

in section, of the top manifold of the apparatus.

Fig. 4 is a bottom plan view of the bottom manifold; and

55 Fig. 5 is a fragmentary sectional detail view on an enlarged scale, substantially on the line 5—5 of Fig. 3, showing one of the joints connecting the manifolds with the headers.

60 Describing the invention with reference to the drawings, my improved heat transfer apparatus, designated as a whole A, comprises one or more, as shown three, hollow headers a, supply and return manifolds a¹ a² connected to the tops and bottoms of said headers, respectively, and adapted to supply a circulation of steam, brine, ammonia or other thermal agent to said headers, and a³ designates the motor of a fan forming part of the apparatus and adapted for discharging a current of air over or through the headers a.

65 As regards their usual features and excepting as hereinafter particularly described and pointed out, all of the above and foregoing devices may be of any usual or approved construction and will be readily understood by persons familiar with the art from an examination of the drawings, without a description thereof in detail.

70 As shown, the headers a, see particularly Fig. 5, are of a type comprising a hollow core 1 made of suitable cast metal, preferably cast iron, and a shell 2 of another metal, desirably an aluminum alloy, formed integral with which are outwardly projecting spaced fins 3. A header of the general type specified is shown, described and claimed in an application for U. S. Letters Patent, therefore, heretofore filed by me on or about October 21, 1929, Serial No. 401,321, to which reference is here made for a description thereof in detail.

75 In accordance with my invention, see particularly Fig. 5, the manifolds a¹ a² are connected to the headers a by hollow fittings 4, which extend through holes formed in the adjacent walls of said manifolds, an end of each of which has screw threaded engagement with a hole formed in an end of a header a and formed on the opposite end of which

is a head 5, the shoulder at the underside of which engages a corresponding shoulder at the inner end of the hole in the manifold as shown at 6. The sleeve fitting 4 is of the type comprising ribs 7 on their inner surface adapted to be engaged by a bar wrench, in a usual manner. Obviously, when the fittings 4 are tightened, the opposed surfaces of the headers a and manifolds $a^1 a^2$ will be drawn into close contact with each other and the joint between them may be sealed and thus rendered fluid-tight by means of a suitable gasket 8 interposed between the opposed surfaces of said headers and manifolds.

The washers 8 may be made of different materials depending upon the use to which the apparatus is to be put. Thus, copper gaskets will preferably be used in connection with steam or hot water circulation, while steel or lead gaskets will be used with ammonia, brine, etc.

A particular advantage arising from the use of the sleeve fittings 4 for connecting the manifolds to the headers is that each joint has but one threaded connection, thus practically reducing the number of screw-threaded connections by more than one-half, as compared with the use of usual connections heretofore commonly used in making such connections.

A further advantage arising from the use of my improved sleeve fittings is that by its use, the over-all dimension of the apparatus between the remote sides of the headers $a^1 a^2$ is reduced to a minimum, the surfaces of the parts connected thereby resting directly in contact with each other.

To attain the object of the invention as it relates to mounting the apparatus, said apparatus is supported by means of rods 9 which extend through holes formed in opposite ends of the bottom manifold a^2 formed on which are heads or abutments 10 upon which said manifold rests and is supported. Said rods 9 also extend through holes formed in the ends of the top manifold to which they are fitted so as to be freely movable and thus support the apparatus in stable operative position. The rods 9 may either be suspension rods, their upper ends being attached to a suitable support, not shown, or, if desired, the lower ends of said rods may be secured in a suitable base or foundation.

With the described construction, it is obvious that the weight of the entire apparatus will be sustained by the rods 9 and that the sleeve fittings 4 which connect the manifolds $a^1 a^2$ to the headers a will be relieved from all stress and duty due to the weight of the apparatus, whereby it is possible to make them of relatively light weight and correspondingly reduce the cost thereof. Also, due to the elimination of screw-threaded connections, as heretofore described, the

machine work on said fittings will be greatly reduced, thus further reducing the cost thereof.

To provide for conveniently and economically forming the holes in the headers a to receive the said hollow fittings 4, holes 11 are formed in said headers diametrically opposite to and in line with the holes formed therein which receive said fittings 4. Said holes 11 are made sufficiently large to permit the passage therethrough of the heads of the fittings 4 and, after the headers a and manifolds $a^1 a^2$ have been assembled, will be closed by means of screw-plugs 12, or the like.

As shown, the supply and return connections 13 and 14 to the top and bottom manifolds $a^1 a^2$, respectively, consist of flange unions 15 which are old and well-known and will be readily understood by persons familiar with the art from an examination of the drawings without a description thereof in detail. Said supply and return connections are sealed by means of suitable gaskets 16, in a usual manner.

In operation, a current of air is adapted to be discharged over or through the headers a by means of the fan a^3 . In order that the apparatus may form a self-contained unit, the fan motor a^3 is preferably mounted at the upper end of a bracket arm 17 which, as shown, is detachably secured to the bottom manifold a^2 , said bracket arm being angular in shape and proportioned to support the fan with its axis substantially in line with the center line of the header or group of headers a .

Also, in accordance with usual practice, the headers a are enclosed in a suitable sheet metal casing, designated as a whole b , the fan 18 being positioned in a hole formed in the rear wall of said casing, and the front of the casing consisting of adjustable louvers 19 by which the air current may be regulated and controlled, as may be desired.

I claim:

A heat transfer unit comprising supply and return manifolds, a plurality of tubular radiator elements connecting said manifolds, each of said tubular elements being a compound structure comprising a hollow casting having integral radiating fins and a separate conduit around which said casting is formed, said conduit being internally threaded at its ends, and hollow headed fittings having threaded engagement with said conduit and bearing on said manifolds.

In witness that I claim the foregoing as my invention, I affix my signature this 28th day of July, 1930.

EDWIN M. BASSLER. 125
